ATTORNEY

UNITED STATES PATENT OFFICE.

ABRAM W. JACKSON, OF NEW YORK, N. Y., ASSIGNOR TO THE DE GROOT ELECTRIC COMPANY, OF NEW YORK.

ELECTRO-THERAPEUTIC APPLIANCE.

SPECIFICATION forming part of Letters Patent No. 431,978, dated July 8, 1890.

Application filed February 20, 1890. Serial No. 341,238. (No model.)

To all whom it may concern:

Be it known that I, ABRAM W. JACKSON, a citizen of the United States, residing in New York, in the county and State of New York, 5 have invented new and useful Improvements in Electro-Therapeutic Appliances, of which the following is a full, clear, and exact description, reference being had to the accompanying drawings, forming part of this specification.

Figure 1 represents a side elevation of my improved appliance, and Fig. 2 represents a sectional view of the same.

My invention relates to improvements in 15 appliances for the cure of varicocele and other affections of the scrotum; and it consists in the arrangement of concavo-convex bimetallic (zinc and copper) segments forming an open ring or clasp with adjusting-screws or their 20 equivalents, in combination with an elastic compressing belt or girdle.

The object of my invention is to compress the exterior or varicose veins and prevent them from becoming filled and distended with 25 blood after having been evacuated by manipulation preparatory to the application of this appliance, and also to furnish a continuous current of electricity to slightly stimulate, revive, and invigorate the parts.

30 In the accompanying drawings, A and B denote the two segments or halves of the concavo-convex bimetallic clasp, which are each provided with lugs C D, having tubular openings through which adjusting screw-rods E are inserted. Surrounding the entire clasp the endless spiral metal spring G extends, located in the concave side of the clasp. This spring has sufficient contractile power to cause the clasp when adjusted in use to prevent 35 the emptied varicose veins from refilling while the degree of compression will not prevent the normal circulation of blood in

the interior vessels. The buttons i serve to attach a pocket or suspensory to support the testicles. The tubes of the respective lugs 45 C are made with screw-threads or female screws, in which the screw-rods work for the adjustment of the clasp, so as to prevent it from becoming detached from its place around the scrotum. About one half of the length 50 of the screw-rods is plain or smooth, so as to work freely in the smooth tubes of the lugs D, and around the screw-rods at the junction of the threaded and plain portions thereof there is fixed a permanent collar H, which 55 serves to limit the approach of the two segments A B toward each other through the action of the spiral spring G. By means of this provision the clasp may be readily adjusted and adapted for use around the parts 60 when of greater or less circumference. The adjusting-screws E may be dispensed with and a detachable screw and nut may be placed between the lugs, the pointed ends of such screw fitting into the lugs to retain this adjusting device in position.

From the foregoing description it will be understood that the appliance can be readily used without the assistance of a physician or surgeon, and all the benefits to be derived 70 from its action as a surgical support or device and as a generator of a continuous current of electricity will be obtained.

What I claim, and desire to secure by Letters Patent as my invention, is—

75 The concavo-convex bimetallic segments A and B, in combination with a contractile elastic spring or band, and adjusting-rods inserted in lugs attached to the segments, as and for the purpose specified.

ABRAM W. JACKSON.
